PRINT PROCESSING MACHINE

Benjamin E. Luboschez, Rochester, N. Y., assignor
to Eastman Kodak Company, Rochester, N. Y.,
a corporation of New Jersey

Application July 16, 1949, Serial No. 105,201

5 Claims. (Cl. 95—89)

1

The present invention relates to photography, and more particularly to a print processing machine.

The present invention is embodied, in the present instance, and by way of illustration only, in a processing machine of a two-solution type primarily, although not necessarily, intended for use in the office or home where the utmost simplicity and ease of operation, as well as freedom from contamination of hands and furniture, are primary requisites. These requisites are achieved by providing the processing liquids or solutions in sealed containers which are opened and effective only during the period when they are in use, and which are closed again automatically immediately thereafter. These containers are easily loaded into position, and may be removed for refilling and occasional cleaning. At the same time, the sealed containers enable the processing solutions to be kept for fairly long periods without spoiling when the machine is not in regular use. A special blotting and/or wiping device contributes to the cleanliness and ease of operation. The machine is simple to operate, and occupies no more space on an office desk than a typewriter.

The invention has, as its principal object, the provision of a new and simplified print processing machine.

A still further object of the invention is the provision of a machine of the class described in which the processing solutions are retained in sealed containers until ready for use; and, after use, the containers are immediately and automatically sealed.

Yet another object of the invention is the provision of a machine of the class described in which the containers are moved selectively into operative position to apply the proper processing solution to the paper print.

And another object of the invention is the provision in such a machine of a replenishable wiping device for removing any excess processing solution.

And yet another object of the invention is the provision of a processing machine which is simple in construction, made of few parts of rugged construction, easy to operate even with unskilled help, cheap to build and highly effective in use.

To these and other ends, the invention resides in certain improvements and combinations of parts, all as will be hereinafter more fully described, the novel features being pointed out in the claims at the end of the specification.

In the drawings:

Fig. 1 is a front elevation view of the print processing machine of the present invention;

2

Fig. 2 is a side elevation view of the machine illustrated in Fig. 1, but on a larger scale than the latter and with one side wall removed, showing the relation of the parts and with one liquid container in applying relation with the print-carrying drum;

Fig. 3 is a view similar to Fig. 2, but showing the other liquid container in liquid-applying relation with the drum; and

Fig. 4 is a perspective view of one of the liquid containers, showing the relation thereto of the liquid-applying roller, and the means for moving the roller to sealing relation when the container is not in use.

Similar reference numerals throughout the various views indicate the same parts.

The print processing machine of the present invention comprises a rectangular box or housing 11 having a rounded lid or cover 12 hinged at 13 to the upper edge 14 of the housing 11. A handle 15 is provided for moving the lid about its hinge 13 to provide access to the interior of the container.

A print-carrying drum 16 is carried by a shaft 17 resting in bearings, not shown, the lower halves of which are carried by the edge 14, while the upper halves are carried by the cover 12 so that when the latter is open, the drum 16 with its shaft 17 may be lifted, as a unit, out of the housing 11, as is deemed apparent. The shaft 17, outside the housing 11, is provided with a handle 18 by which the drum may be rotated for reasons to be later described.

The print 21 to be processed is attached, face outward, to the drum 16 by means of a stainless steel clip 22 which fits snugly into the drum surface and offers a minimum of obstruction. This clip holds the print by its leading edge, and the opposite or trailing edge of the paper print is left free so as to allow for any stretching that might take place during processing. However, if desired, the trailing end may also be clipped to the drum, but in such an event a spring device must be provided to take up any stretch and to pull the paper taut. However, the single strip is preferred, and the double clip is not necessary if the drum is always rotated in the proper direction.

A pawl and ratchet, not shown, may be provided for preventing improper rotation of the drum. As such pawl and ratchet devices are well known and form no part of the present invention, details thereof are not deemed necessary. During the attaching of the print 21 to the drum 16, the cover 12 is moved to its open position by handle 15.

A shaft 23 is journaled in the opposite sides of the housing 11 below the shaft 17 and in substantial vertical alignment therewith. A portion of this shaft projecting outside the housing 11 has secured thereto a lever arm 24 for rocking the shaft 23 selectively from the position shown in Fig. 2 to that shown in Fig. 3, or from the position shown in Fig. 3 to that illustrated in Fig. 2, or to a neutral position. The shaft 23 has positioned in fixed relation thereon a bracket formed with normally spaced arms 25 and 26 adapted to receive detachably a pair of liquid containers, broadly designated by the numerals 27 and 28. The container 27 may, for example, contain a developing solution, while container 28 may have a fixing solution. However, other solutions or liquid may be employed, depending on the process to be carried out.

As both containers 27 and 28 are identical in structure, only one will be described in detail, and corresponding parts of the other container will be designated by the same numerals. Each container is formed with a bottom 31, opposite sides 32, a back 33, a front wall 34 and a top 35, the front end of which is inclined, as shown at 36. A filling opening, closed and sealed by a cap 41, is provided in top 35. The interior of the container is divided by a vertical partition 37 to provide a liquid storage compartment 38 and a liquid distributing compartment 39. The lower end of partition 37 terminates short of the bottom 31 to control the height of the liquid in compartment 39, as is deemed apparent.

A roller 46 is mounted for rotation in the compartment 39 and has a portion projecting through a slot 40 in the inclined wall 36, as shown in Figs. 2 to 4. The slot 40 has a length equal to the length of the roll 46, and a width less than the diameter of the roll so that the latter cannot pass through the slot. The roller is covered with rubber and dips into the liquid in the compartment 39, as shown in Figs. 2 and 3. The axle 41 of the roller 46 runs in inclined or oblique slots 42 formed in the opposite side walls of compartment 39. Means, such as coil springs 43, or other suitable means, engage axle 41 to move the roller 46 outwardly to seal the slot 40 when the container is not in use, as shown in Fig. 4, thereby completely sealing the liquid in the container. It will be apparent that if pressure is applied to the roller in a downward direction at right angles to the face 36, the roller will be moved out of sealing relation with the slot 40 in a manner and for a reason to be later pointed out. The containers when mounted on arm 25-26 are held in position thereon by spring clips 43, see Figs. 2 and 3.

When the machine is to be used, the cover 12 is raised, and a print 21 is attached to the drum 16 by means of clip 22. The lever 24 is then rocked to the position shown in Fig. 2 to bring the left container 27 into position so that the roller 46 thereof engages the surface of the drum 16 radially and with the tangential plane of contact parallel to the face 36. When in this position, the contact of the drum with the roller 46 will serve to move the latter inwardly against the action of the springs 43 to unseal the slot 40 and to also free the roller for rotation. Now, by rotating handle 18, the drum 16 is rotated and the roller 46 is also rotated and picks up liquid, such as the developer, and applies the liquid to the print 21 to develop the latter. After a sufficient length of time and/or a number of rotations of the drum 16, development is complete, and the

lever 23 is moved to the position shown in Fig. 3 to rock shaft 23 to move container 27 to an inoperative position and simultaneously position the right container 28 in operative relation with its roller 46 in engagement with drum 16 so that upon rotation of the latter the liquid in container 28, which may be a fixing solution, is applied to the print. Both containers also may be moved to their inoperative position by moving the lever 24 to its central or neutral position, as shown in dotted lines at 44 in Fig. 2.

Thus, by shifting lever 24, a rocking movement may be imparted to shaft 23 to move selectively one of the liquid containers 27 or 28 into operative position to apply the proper processing liquid to the print. When either container is moved to its inoperative position, the springs 43 serve to move the roller 46 thereof into sealing relation with the slot 40, the advantages of which are deemed apparent. The roller 46 applies an even coating of processing solutions. A door 45 formed in the housing affords access to the containers. While the drum 16 has been illustrated as manually rotated by handle 18, it is apparent that a small motor or other prime mover may be connected to the shaft 17 to rotate the drum 16.

In order to remove surplus liquid both during and after processing, the present invention has incorporated into the cover 12 a blotting and wiping device. When the cover is pulled down, as shown in Figs. 2 and 3, this device automatically comes into action, but when the cover is open, or latched slightly open by any suitable means, the wiper becomes inactive or inoperative. This is a very simple and inexpensive method of controlling the wiping action. The wiper consists of a length of webs 50 of cheap absorbent material such, for example, as non-fluffy paper or cotton, which has the same width as the drum and is drawn lightly over the latter as it is rotated so that the print 16 is brushed lightly over by the wiping material. At the same time, the material is pulled along slowly so that a fresh part of the material is brought into action.

To secure this result, the material is positioned on a roll 51 from which the web is unwound and passed over a guide roll 52, the drum surface, guide roll 53 to a take-up roll 54. The axle of the take-up reel 54 is provided with a ratchet 55 which is engaged by a pawl 56 carried on one end of a rod 57 pivoted at 58. The other end 59 of rod 57 is positioned in the path of a pin 60 carried by a drum 16 so that on each rotation of the drum the pin 60 engages rod 57 to pivot the latter to cause pawl 56 to engage ratchet 55 to turn roll 54 a definite amount to wind up a portion of the wiper web 50. Thus, a new and unused portion of the wiping web is continually supplied to wipe the print and remove excess solution. The magnitude of the pull-through may be adjusted to suit the type of processing being carried on. This variation in pull-through may be secured, for example, by adjusting the position of the pivot point 58 to control the throw of the pawl 56. In addition to the pawl and ratchet means, the take-up roll 54 may be rotated manually by means of a handle 61 secured to the take-up roll axle. This manual arrangement enables the operator to move any contaminated part of the web 50 out of the way before processing a new print. When the web has been used, it is discarded and replaced by a new roll. The cost of such replacement is not considered prohibitive

because only a few inches must be used with each print.

It is to be noted that since the wiper web 50 passes over all of the part of the drum, the latter is always clean, and there is small likelihood of any solution creeping under the edge of the print. Prints of any size, up to the drum circumference, may be processed without contamination of the drum, although with small prints there will necessarily be a relative waste of processing solutions. The device is very flexible, and is easily adapted to the needs of various processing systems. The wiper device may be brought in and out of action at any stage in the proceeding merely by positioning the cover 12.

For final drying of the print, the rocking lever 24 is moved to its neutral position, as shown dotted in Fig. 2, and the drum 16 may be rotated a few times to remove surplus moisture or solutions. The print is then sufficiently dry for most purposes since at no stage in the processing does it become wet enough for the paper to absorb much liquid. However, where extra complications are warranted, heating arrangements in the form of infrared lamps or similar devices may be positioned adjacent to the drum.

The present invention thus provides a print processing machine which is simple in construction, easy to operate, and in which the processing solutions are retained in sealed containers until ready for use, at which time the containers may be moved selectively into operative position. The processed prints are easily and quickly dried before removal from the machine. Furthermore, when the liquid containers are moved to an inoperative position they are automatically and completely sealed until again used.

While one embodiment of the invention has been disclosed, it is to be understood that the inventive idea may be carried out in a number of ways. This application is, therefore, not to be limited to the precise details described, but is intended to cover all variations and modifications thereof falling within the scope of the appended claims.

What I claim is:

1. A print processing machine comprising in combination, a housing, a print-carrying drum rotatably mounted in said housing, means for securing a print to be processed to said drum for movement therewith, means for applying a processing liquid to said print, a wiping device engaging said drum to remove excess processing liquid, and means actuated by said drum to move said device intermittently.

2. A print processing machine comprising, in combination, a housing, a print-carrying drum rotatably mounted in said housing, means for securing a print to be processed to said drum for movement therewith, means for applying a processing liquid to said print, a wiping device comprising a renewable web of absorbent material engaging said drum to remove excess processing liquid, and means controlled by said drum for

imparting intermittent movement to said device to present clean portions of the latter to said drum.

3. A print processing machine comprising, in combination, a housing, a print-carrying roller rotatably mounted in said housing, means for securing a print to be processed to said drum for movement therewith, means for applying a processing liquid to said print, a wiping device comprising a web of absorbent material engaging said drum to remove excess processing liquid, and means controlled by the rotation of said drum to move said web progressively to bring unused portions of said web into contact with said drum.

4. A print processing machine comprising, in combination, a housing, a print-carrying roller rotatably mounted in said housing, means for securing a print to be processed to said drum for movement therewith, means for applying a processing liquid to said print, a wiping device comprising a web of absorbent material engaging said drum to remove excess processing liquid, means controlled by the rotation of said drum to move said web progressively automatically to bring unused portions of said web into contact with said drum, and separate manual means for moving said web.

5. A print processing machine comprising, in combination, a housing, a print-carrying drum rotatably mounted in said housing, means for securing a print to said drum for movement therewith, a shaft rockably mounted in said housing, a liquid applying member mounted on said shaft, means for rocking said shaft to move selectively said member into engagement with said drum to apply a processing liquid to said print, a web of absorbent material engaging said drum to remove excess processing liquid therefrom, and means controlled by said drum to advance said web to position an unused portion of the web in contact with said drum.
